The ornamental design for a shelf joint, as shown and described.

DESCRIPTION

FIG. 1 is a front elevational view of a shelf joint showing my new design;

FIG. 2 is a rear elevational view;

FIG. 3 is a top plan view;

FIG. 4 is a bottom plan view;

FIG. 5 is a left side elevational view;

FIG. 6 is a right side elevational view;

FIG. 7 is a sectional view taken in the direction of the arrows on line 7—7 of FIG. 1;

FIG. 8 is a sectional view taken in the direction of the arrows on line 8—8 of FIG. 1;

FIG. 9 is a sectional view taken in the direction of the arrows on line 9—9 of FIG. 3;

FIG. 10 is a top, front and right side perspective view;

FIG. 11 is an exploded top, front and right side perspective view; and,

FIG. 12 is a reduced perspective view, the broken line showing of the pipes, box, and additional connectors being for illustrative purposes only.
